United States Patent Office.

RODMAN BACKUS, OF ALBANY, NEW YORK.

Letters Patent No. 95,182; dated September 28, 1869.

BASE-BURNING STOVE.

The Schedule referred to in these Letters Patent and making part of the same.

To all whom it may concern:

Be it known that I, RODMAN BACKUS, of the city, and county of Albany, in the State of New York, have invented certain new and useful Improvements on Magazine Parlor-Heaters; and I do hereby declare that the following is a full, clear, and exact description thereof, reference being had to the accompanying drawings, making part of this specification, in which—

Figure 1, sheet 1, is a diametrical section through a magazine parlor-stove having my invention applied to it.

Figure 2, sheet 2, is a side elevation of the perforated lower section of the stove, with a portion broken away to expose the fire-pot.

Figure 3, sheet 2, is a section taken through fig. 2, in the horizontal plane indicated by line x x .

Similar letters of reference indicate corresponding parts in the several figures.

This invention relates to certain novel improvements on fuel magazine parlor-heaters, which are so constructed that the products of combustion, after rising from the fire-pot, ascend through an illuminating section, through a vertical flue-space surrounding the magazine, and thence pass off into the main flue or chimney.

The object of my invention is mainly to provide such a stove with a fire-pot, which is composed of soapstone, or other suitable mineral bricks, applied in an open or skeleton frame in such manner that the bricks will be exposed to view through this frame, and to arrange this fire-pot within a perforated case, which forms a portion of the outer wall of the stove, whereby heat will be radiated directly from the mineral lining of the pot into the room, as will be hereinafter explained.

Another object of my invention is to construct a brick-lined fire-pot, which is enclosed by a perforated casing of a prismatic or many-sided form internally and externally, for the purpose of preventing lodgement of ashes around the sides of the body of coals, and also for allowing currents of air to ascend into the body of coals at the angles formed by the junction of the vertical edges of the brick lining, as will be hereinafter explained.

To enable others skilled in the art to understand my invention, I will describe its construction and operation.

In the accompanying drawings, A represents the base section of the heater, and B is a perforated section, which is mounted upon section A, and forms part of the outer wall of the heater.

Within the perforated wall B, and supported upon the base section, is an elevated grate-section, C, in which a circular movable dumping-grate, b, is supported upon a bearer, b'. Upon this grate-section the

fire-pot D is supported and held in place in any suitable manner.

Between this fire-pot, D, and the perforated section, B, is an air-circulating space, g, extending entirely around the fire-pot, and communicating with the external air through the perforations made through the section B. The annular space g is closed at top by the flange f, of a ring, E, which flange also serves to hold the fire-pot in place at its upper end, as shown in fig. 1.

Upon the ring E, the illuminating-section F is supported, with its hinged mica frames or doors h, and upon this section F, the drum G is supported and held in place, carrying on its upper end the cap H; with its cover I.

The magazine K, with its removable foot k, may be suspended from the cap H in the usual well-known manner, and provided with a feed-opening through its upper end, closed by a valve, l.

By means of the flue-passage j, constructed in the space formed between the magazine and the drum G, the products of combustion are caused to rise as high as the cap H, before passing off through the exit-pipe.

It will be seen from the above description that the general arrangement of the heater is such that the products of combustion all rise above the illuminating-section, and do not dive down below the upper end of the fire-pot. It will also be seen that the fire-pot is enclosed within a section, B, which constitutes part of the outer wall of the stove, and forms an annular space, g, for the circulation and heating of air by direct radiation from, and by contact with the sides of the fire-pot, which chamber is separated from the combustion-chamber, enclosed by the illuminated section by the annular diaphragm or flange f.

The fire-pot D, which I prefer to make of a polygonal shape, is composed partly of soapstone or other suitable mineral brick sections d d, and partly of metal. The metal part consists of narrow vertical bars e', of angular form in cross-section, united at their extremities to narrow annular bands, e e, as shown in fig. 2. These bands and strips constitute an open or skeleton frame, which is adapted for receiving within it and keeping in place the fire-brick sections d, the abutting edges of which are suitably bevelled, as shown in fig. 3. The object of employing a skeleton frame is, that I may be enabled to firmly hold the brick lining, and at the same time have the outer surfaces of this lining exposed, as shown in figs. 2 and 3.

It is well known that heat which is radiated from highly heated metallic fire-pots, is very dry and unpleasant, which is not the case with substances of which fire-bricks are made. I therefore expose nearly the whole of the outer surface of the fire-brick lining, and arrange this fire-pot within a casing or outer wall,

B, which is perforated in such manner as to allow a direct radiation of heat into the room from the fire-pot through the spaces or perforations in said wall B.

For the purpose of protecting the upper ends of the fire-bricks, and at the same time affording a slightly flaring mouth to the fire-pot D, an upwardly-flaring ring, D', is arranged upon the fire-pot, as shown in fig. 1, which ring can be tilted when it is desired to remove any one or more of the brick sections d.

To facilitate the removal of the brick sections d, to repair the fire-pot, I employ doors h for the openings of the illuminating-section, which are hinged at their lower ends at i, so that if desirable, all the doors can be swung open at one time, to allow free access into the combustion-chamber and fire-pot. I do not confine myself, as far so the skeleton frame or fire-brick lining are concerned, to a prismatic or many-sided fire-pot, as the metallic portion of such a pot might be made circular.

The advantages which result from the use of a fire-pot presenting obtuse angles at the junction of its bricks are, that the coals will not lie so close to the sides of this pot as they would if it were circular upon its inner side, and vertical air-ducts will be left which will allow the ascent of air through the fire-pot to support combustion, and also allow ashes to fall freely into the ash-pit from the sides of the bed of coals, when the grate is shaken. In practice, the perforations through case B may extend entirely around it,

and they may be made so as to give this case a very beautiful and ornamental appearance.

I have herein described a fire-brick-lined fire-pot of prismatic form, with the metal casing which encloses the lining made so as to expose the fire-bricks through it, but I do not desire to be understood as confining myself, so far as the prismatic form is concerned, to a lined fire-pot, as such form, if adopted for an iron pot without lining or openings through its sides, will be found very advantageous.

I do not claim as my invention such arrangements as are shown in the Letters Patent of Porter Dodge, February 21, 1865, D. G. Littlefield, June 25, 1861, and D. G. Littlefield, December 9, 1862.

Having described my invention,

What I claim as new, and desire to secure by Letters Patent, is—

1. The combination of a fuel-magazine, a fire-pot whose fire-brick lining is arranged within a skeleton frame, and a perforated casing located beneath illuminating-windows, substantially as described.

2. A prismatic or many-sided fire-pot, capped by a removable guard-ring, D, and arranged beneath a fuel-magazine, substantially as described.

3. Removable fire-bricks d, movable ring D', and doors h, hinged substantially as described.
